BOTTLE

Joseph Marder, Pittsburgh, Pa., assignor to Lotta Cola
Company, Pittsburgh, Pa.

Filed May 13, 1960, Ser. No. 60,582

Term of patent 14 years

(Cl. D58—8)

Fig. 1.

Fig. 2.

Fig. 1 is a front view of a bottle showing my new design.
Fig. 2 is a top plan view.

The rear of the bottle is the same as the front thereof as is indicated in Fig. 2.

I claim:

The ornamental design for a bottle, substantially as shown and described.
